UNITED STATES PATENT OFFICE

HERMAN J. ENGBRECHT, OF CHICAGO, ILLINOIS

RECEPTACLE EVACUATING APPARATUS

Application filed March 7, 1925. Serial No. 13,819.

My invention relates generally to apparatus for evacuating receptacles of their contents and more especially to the evacuating of oil-receptacles, as for example, and more particularly, crank-cases of automobile engines as one of the steps in the changing of the oil in the receptacle.

My object, generally stated, is to provide a novel, simple and inexpensive construction of apparatus for expeditiously performing the evacuating operation.

Certain of my more specific objects are as follows:

To provide an apparatus, for the purpose stated, employing, for its operation, fluid-pressure, as for example compressed air, presenting the advantage, among others, of permitting of the utilizing of the compressed-air-producing mechanism commonly provided at service stations for tire inflation, and requiring only relatively inexpensive additional equipment.

To provide for the rapid and effective evacuation of the receptacle, particularly a crank-case of an automobile engine.

To provide an apparatus for the purpose stated comprising the minimum number of moving parts to the end that likelihood of the apparatus becoming out of order, will be reduced to the minimum.

To provide an apparatus for the purpose stated the operation of which may be accurately, and easily, controlled.

To provide an apparatus whereby the evacuating operation may be effected without soiling the hands or the clothes of the operator.

To provide a novel and simple device for manipulation by the operator by which the force, to be employed in the evacuating operation, may be exerted on the liquid to be removed from the receptacle.

To provide such a device whereby it may be readily applied to, and removed from, an outlet at the bottom of the receptacle, as for example, and more particularly, the outlet of a crank-case of an automobile engine.

To provide such a device for co-operation with a valve-controlled outlet of a receptacle operating upon its application to such an

outlet to automatically open the valve of said outlet to the device.

To provide a novel, simple and inexpensive construction of hollow drain-adapter, through which the crank-case is evacuated, for use more especially as a part of my improved complete apparatus, which may be secured in the openings commonly provided in automobile crank-cases for receiving the ordinary drain plugs, and particularly to provide such an adapter which may be used on all of the different kinds of crank-cases, as a substitute for the ordinary drain-plugs provided thereon.

To provide an adapter of the character stated equipped at its drain-outlet with a self-closing valve adapted to be automatically opened in the application of the evacuating apparatus thereto, and more particularly presenting a plurality of drain outlets one of which is equipped with the valve referred to and the other of which is adapted to receive an ordinary drain plug and through which the case may be drained in the ordinary way by removing the plug.

Referring to the accompanying drawings wherein my invention is illustrated in its preferred embodiment for evacuating the crank-cases of automobile engines:—

Figure 1 is a view, partly diagrammatic, of the crank-case-evacuating apparatus showing it connected, in operative position, with a crank-case of an automobile the drain outlet of which is equipped with my improved adapter. Figure 1^a is a broken, enlarged, section taken at the line 1^a on Fig. 2 and viewed in the direction of the arrow. Figure 2 is a view in vertical, sectional, elevation of the vacuum-tank assembly forming a part of the apparatus, and comprising an ejector-device for creating vacuum in the tank. Figure 3 is an enlarged, similar, view of the ejector device. Figure 4 is a broken view in longitudinal sectional elevation of a portable, handle-equipped, valved extension pipe device, forming a part of the apparatus, and through which the suction is applied to the outlet of the crank-case, the section being taken at the line 4—4 on Fig. 6 and viewed in the direction of the arrows. Fig-

ure 5 is a broken section taken at the lines 5—5 on Fig. 4 and viewed in the direction of the arrows. Figure 6 is an edge view of the valved handle-portion of the extension pipe device. Figure 7 is a view in vertical sectional elevation of the adapter-equipped portion of the crank-case and that end of the extension pipe device which directly co-operates therewith, the pipe device being shown 10 disengaged from the adapter, but in alignment therewith. Figure 8 is a similar view showing the extension pipe device moved into the position it assumes when engaged in operative position with the adapter; and Figure 9, a broken, sectional, view of the lower 15 portion of a crank-case of the side-outlet type showing my improved adapter applied thereto.

The apparatus, in accordance with the preferred illustrated embodiment of my invention, comprises a vacuum-tank unit represented generally at 10 and comprising a hollow column 11 surmounted by a vacuum-tank 12 shown as formed of a base-plate 13 having a depending circular flange 14 with which the upper end of the column 11 is telescoped and to which latter the plate 13 is secured; a cover plate 16 and an intermediate tubular side-wall-forming portion 17, preferably of glass, telescoped at its ends with circular flanges 18 and 19 on the plates 13 and 16, respectively, the portion 17 being surrounded by a wire-screen guard 18 telescoped at its ends with flanges 19 and 20 on the plates 13 and 16, respectively. The plates 13 and 16 and tubular portion 17 are held rigidly together to render the tank 12 hermetically sealed, by means of a tubular member 21 screwed at its lower open end into the plate 13, this member extending upwardly through a packing-equipped opening 22 in the cover-plate 16, and a nut 23 screwed upon the threaded portion 24 of the tubular member 21 and against the cover plate 16 and its packing shown at 16^a.

The vacuum is produced in the tank 12 by means of an ejector-device represented generally at 25, and interposed in, and forming a part of, the tubular member 21. The device 25 comprises a casing 26 located in the opening 22 in the cover-plate 16 and upon which the nut 23 is screwed, as stated, the lower threaded open end of the casing 26 screwing upon the upper end of the lower pipe-section 27 of the tubular member 21 and containing a passage 28 opening into the pipe-section 27 and into the upper-end of the tank 12. The upper end of the casing 26 contains a threaded socket 29 into which the lower end of the upper pipe-section 30 of the tubular member 21 is screwed. The ejector-casing contains, above the passage 28, a centrally-disposed passage 31 into the lower end of which the upper end of a pipe 32 located in the pipe 27, in spaced relation to the side-walls

of the latter, is screwed, this pipe being provided for communication with a supply of fluid pressure as for example compressed-air, as hereinafter described. Screwed into the upper end of the passage 31 is a nozzle 33 which extends into a chamber 34 in the casing 26 in spaced relation to the side wall thereof, this chamber being preferably of the shape shown in the drawings and opening at its lower end into the upper end of the vacuum-tank 12 through a port 35 in the casing 26 and through which port the air, in evacuating the tank 12, is drawn by the ejector action of the device. The ejector device also comprises a tubular member 36 which screws into the socket 29 and forms the top wall of the suction-chamber 34. The member 36 contains a passage 37 constricted at 38 and flaring upwardly and downwardly, respectively, above and below this restricted portion, as represented at 39 and 40, this passage, which opens at its lower end into the chamber 34, being vertically alined with the nozzle 33. The nozzle 33 contains a passage 39 communicating at its lower end with the pipe 32 and opening at its upper end into the chamber 34, the passage 39 at its upper extremity being restricted at 41 with the side wall of its restricted portion flaring upwardly as represented at 42.

It will be understood from the foregoing that fluid-pressure supplied to the pipe 32 and flowing through the nozzle 33 and the member 36 induces suction in the tank 12 through the passage 35 and consequently suction in the pipe 27, through the passage 28, for the purpose hereinafter stated. 100

The fluid-pressure supply referred to is shown as comprising a storage tank 44 communicating, by pipes 45, with an air-compressor 46, the tank 44 being connected with a pipe 47 which extends upwardly into the column 11 and thence laterally through the side-wall thereof, the pipe 47 being connected, at its outer end, with a flexible hose-line 48 which is connected at its outer end with an extension pipe-device, hereinafter described, through which the compressed air is led, under valve control to a flexible hose-line 49 connected with the lower laterally-extending, portion of the pipe 32 which projects through the side-wall of the column 11.

The rigid extension pipe-device, hereinbefore referred to, and represented generally at 50, and through which the evacuating suction is applied to the outlet of the crank-case the contents of which are to be removed, comprises a pipe-section 51 preferably formed with a transparent section 51^a and equipped at one end with a hand-grip 52 of the pistol-grip type. The hand-grip 52 contains a passage 53 which opens at one end into the pipe 51 and at its opposite end, which is equipped with an attaching nipple 53^a, into a flexible hose-line 54 connected with the laterally-ex- 120
125
130

tending lower end portion of a pipe 55 located in the column 11 and communicating at its upper end with the lower end of a passage 56 in the base-plate 13 which passage communicates with the lower open end of the pipe 27.

The hand-grip 52 is provided with nipples 57 and 58 to which the hose-lines 48 and 49 are connected, respectively, these nipples opening into passages 59 and 60, respectively, in the hand-grip. The passages 59 and 60 open into valve-chambers 61 and 62, respectively, separated by a partition 63 containing an opening 64 presenting a valve-seat 65 with 15 which a reciprocable valve 66 cooperates, this valve being actuated by valve stem 66^a guided in a plug 67 in the chamber 62, and being yieldingly held against the seat 65 by the pressure of the air in the chamber 61. The 20 outer end of the valve stem 66^a extends normally into a position to be engaged, and forced inwardly to open position, by a hand-lever 68 fulcrumed at 69 on the body-portion of the hand-grip 52 and yieldingly pressed 25 away from the valve 66 by a spring 70.

The arrangement of the parts described is such that upon pressing the lever 68 forwardly, by the thumb of the operator, air is permitted to flow from the air-supply tank 44 30 and thence through the ejector-device 25 producing suction as hereinbefore described, which exerts suction in the pipe section 51.

In the particular arrangement shown the receptacle (crank-case) to be evacuated is 35 provided at its drain-outlet with an inwardly-opening check-valve positioned to be opened by externally applied force, and the outer end portion of the pipe-extension 50 is so constructed that this valve is opened and an air-tight joint established between the pipe-device 50 and the casing of the valve referred to, by the act of applying the pipe device 50 thereto. The joint referred to, in the particular construction shown, is produced by 45 providing the outer end of the pipe-section 51 with a gasket 71 located in the outer end of a sleeve 72 slidably-mounted on the outer end of the pipe-section 51, the gasket being held in place against a flange 73 on the sleeve 50 by a threaded washer 74 screwed into the threaded portion 75 of the sleeve 72. The sleeve is normally yieldingly pressed forwardly by a coil-spring 76 positioned in the sleeve and in a recess 77 in the end of the 55 pipe section 51, and bearing at its ends against the bottom wall of the recess 77 and the washer 74, respectively, in which position of the sleeve it engages at a flange 78 thereon with a shoulder 79 provided by the enlarged bearing-portion 80 of the pipe 51.

The means on pipe extension 50 for opening the check-valve referred to comprises a pin 81 rigidly secured at one end in a ported cross-wall 82 in the portion 80 of the pipe 50, the outer end of this pin, which is arranged

concentric with the pipe 51, extending adjacent the gasket 71 as shown.

The preferred form of drain-adapter shown and represented generally at 83, comprises a body-portion containing there-through an opening 84 one end of which is restricted, as represented at 85, at which portion the body of the adapter is of reduced diameter, as represented at 86, and forms a valve-seat 87, the wall of this opening at its 75 other end being internally threaded as represented at 88. The body portion is provided with a laterally-extending boss 89 disposed at substantially a right angle to the plane of the opening 84 and internally and externally 80 threaded, as represented at 90 and 91. The adapter also comprises an inwardly-opening check-valve 92 shown as in the form of a ball, which is normally yielding held against the seat 87 by a coil-spring 93 located in the opening 84 and confined between the valve 92 and a hollow member hereinafter referred to 85 screwed into the threaded portion 88 of the adapter.

The arrangement of the parts described is 90 such that upon applying the extension pipe-device 50 to the reduced end-portion 86 of the adapter to engage the gasket 71 with the portion 86, and pushing the pipe-device 50 toward the adapter, the gasket is caused to 95 make a tight joint with the portion 86, and the pipe 51, together with the pin 81, moves forwardly to the position shown in Fig. 8, the pin in this operation unseating the valve 92 in opposition to the spring 93 and establishing communication between the pipe 51 and the interior of the adapter.

The adapter illustrated is adapted for universal application to crank-cases. In Fig. 7 I have shown it as installed in the crank-case 105 of a Ford engine represented at 94, the adapter in such installation being screwed at its boss 89 into the internally-threaded drain-outlet 95 of the crank-case 94, and the end thereof, threaded at 88 closed by a plug 96, 110 screwed into a bushing 97 engaging the threads 88 of the adapter. In Fig. 8 I have shown the adapter as installed in a crank-case of a different construction, represented at 98 and containing a larger drain-outlet 115 98, the adapter in this construction being secured at the drain-opening 99 by a bushing 100 externally threaded at 101, at which portion it screws into the drain-outlet 99, and internally threaded at 102 into which portion the boss 89 of the adapter is screwed. 120 In Fig. 9 the adapter is shown as installed in a crank-case, shown at 103, of a type where-in its drain-outlet, represented at 104, opens through a side-wall of the case. In this installation the connection between the adapter and case 103 is made at the threaded portion 88 of the adapter through the medium of a bushing 105 screwed at one end into the drain-outlet 104 and at its opposite end into 125 the threaded portion 88 of the adapter, a plug

106 being screwed into the boss 89 of the adapter which latter is so positioned that its boss projects downwardly.

In the use of the apparatus the operator 5 grasping the hand-grip 52 applies the outer end of the extension pipe-device 50 to the adapter as shown in Fig. 8 and as herein-before described, and presses on the valve-controlling lever 68, which opens the valve 62 and allows air under pressure to flow from the tank 44 through the ejector device 25, thus producing suction in the tank 12 which is communicated to the pipe 51 and exerted on the oil in the crank-case, which is quickly 10 evacuated of its oil content, the latter being drawn into the tank 12 through the pipe 27 wherein it is exposed to view.

The tank 12 is shown as provided with a draw-off pipe 107, valved at 108, through 20 which the oil in this tank may be allowed to flow to any desired point, as for example, into a storage tank 109 shown as communicating with a pump 110 for discharging the oil from the tank, as for example, into cars 25 (not shown).

One of the primary advantages of my apparatus is that it may be installed in oil-filling stations, as commonly provided, with the minimum of expenditure for additional 30 equipment and maintenance, inasmuch as the air-compressing and air-storage apparatus provided, at such stations, for tire-inflation, may be used to supply the compressed air used in the operating of my oil draining apparatus.

The provision of the extension pipe-device especially when equipped with means controlling the exertion of suction therein, is of advantage as it affords a means for connection with the outlet of the crank-case, which may be readily and conveniently manipulated by the operator, and where used in the arrangement shown obviates the necessity of preliminarily removing or displacing any 45 of the parts of the automobile.

The adapter, as shown, presents the advantage of universal application to crank-cases of different forms, while affording, preferably, by the provision of a removable solid 50 drain-plug, means by which the crank-case may be drained by gravity flow alone if desired.

While the several features of my apparatus are shown as combined to form an oil-draining unit, it will be understood that these 55 several features are capable of use separately in other combinations, wherein their several respective functions and advantages may be availed of. In this connection it may be 60 stated that whereas the apparatus shown includes a special type of adapter through which the oil flows by gravity by reason of the location of its outlet at a point below the bottom of the crank-case, such is not necessary in the availing of certain advantages

of my invention, as the apparatus may be used where the drain outlet is extended upwardly above the bottom of the crank-case even to a point above the normal oil-level 70 therein. Furthermore, the invention may be utilized to great advantage in the evacuating of receptacles through openings therein above their bottoms, as for example, in the case of the casings of transmission gears, in which case the suction pipe of the apparatus would be introduced downwardly into the contents of the receptacle to be evacuated to 75 emerge it therein.

While I have illustrated and described a particular embodiment of my invention it will be understood that various changes and alterations may be made therein without departing from the spirit of my invention.

What I claim as new, and desire to secure by Letters Patent, is:

1. The combination with an oil receptacle, such as the crank-case of an automobile, having a check-valve-equipped discharge outlet opening below the normal oil level in the receptacle, of a pipe device, means for detachably connecting said pipe device to said discharge outlet, means for automatically opening said valve, and means for exerting suction in said pipe-device.

2. The combination with an oil receptacle, such as the crank case of an automobile, to be evacuated of its oil-content and containing a bottom discharge outlet, of a valve on said outlet, an extension suction-pipe device for detachable connection with said drain outlet and having a hand grip, means for opening said valve when said pipe is connected with said discharging outlet means connected with said pipe device for creating suction in the latter, and means on said grip controlling the production of suction in said pipe device and comprising a controlling element positioned to be operated by the thumb of the operator grasping said hand grip.

3. In apparatus for the purpose set forth, the combination of fluid-pressure-operated suction producing means, a suction-pipe device communicating with said suction-producing means and adapted to be applied to a receptacle to be evacuated, a conduit through which the fluid for actuating said suction-producing means is supplied to the latter, said conduit extending in said pipe-device, and means on said pipe-device for controlling the flow of fluid-pressure to said suction-producing means.

4. In suction-producing apparatus, the combination of a vacuum tank, a suction pipe in said tank open at one end for communication with the space in which suction is to be exerted and opening into said tank adjacent the upper end of the latter, an ejector-device adjacent the upper end of said tank with its suction-inlet communicating with said tank, and a pipe for directing fluid

pressure into said ejector-device extending through said first-named pipe and in spaced relation thereto.

5. In suction-producing apparatus, the combination of a vacuum tank formed in sections and presenting end-forming portions, a suction-pipe in said tank and connected at its lower open end with the lower one of said end portions, said last-referred 10 to end portion containing a passage communicating with said pipe, an ejector-device connected with the upper end of said pipe, the top of said ejector-device containing a passage which opens into the upper end of 15 said vacuum tank and into the upper end of said pipe, the suction-inlet of said ejector-device opening into the upper portion of said tank, and a pipe for supplying fluid-pressure to said ejector-device extending through 20 said first-named pipe and in spaced relation thereto and communicating with the pressure-inlet of said ejector-device.

6. Apparatus for evacuating the crank cases of automobiles through a lower drain 25 outlet thereof comprising a check valve in said outlet, a rigid pipe having an inlet at which it is adapted to be detachably connected with said outlet, means on said pipe for opening said check valve, and means for producing suction in said pipe, said pipe being of such length that it extends from such an outlet to which it is applied, substantially to the side edge of the automobile.

7. Apparatus for evacuating the crank 35 cases of automobiles through a lower drain outlet thereof comprising, a check valve on said drain outlet, a conduit comprising a flexible pipe section and a rigid pipe section, the inlet end of said rigid pipe section being 40 adapted for detachable communication with said outlet of the crank case and of such length that it extends from the outlet to which it is applied substantially to the side edge of the automobile, means on said rigid 45 pipe section for opening said check valve, and means for producing flow of the lubricant from said outlet through said conduit.

8. Apparatus for evacuating the crank 50 cases of automobiles through a lower drain outlet thereof, comprising a check valve on said outlet, suction-producing means, a conduit in communication with said means and comprising a flexible pipe section and a rigid pipe section, and means on the rigid pipe section 55 for opening said valve, the inlet end of said rigid-pipe section being adapted for detachable communication with the outlet of crank cases and of such length that it extends from such an outlet to which it is applied, substantially to the side edge of the automobile.

9. Apparatus for evacuating the crank 60 cases of automobiles through a lower drain outlet thereof comprising a check valve in 65 said outlet, a flexible pipe section and a rigid

pipe section, the inlet end of said rigid pipe section being adapted for communication with said outlet of crank cases and of such length that it extends from such an outlet to which it is applied substantially to the side 70 edge of the automobile, means on said rigid pipe section for opening said check valve, means for producing flow of the lubricant from such an outlet through said conduit, and a receptacle into which the lubricant dis- 75 charges through said conduit.

10. Apparatus for evacuating the crank cases of automobiles through a lower drain outlet thereof comprising, a valve in said outlet, a receptacle, means for producing suction 80 in said receptacle, a conduit in communication with said receptacle and comprising a flexible pipe section and a rigid pipe section, the inlet end of said rigid pipe section being adapted for detachable communication 85 with the outlet of crank cases and of such length that it extends from such an outlet to which it is applied substantially to the side edge of the automobile and means on said rigid pipe for opening said valve in said outlet. 90

11. Apparatus for evacuating the crank cases of automobiles through lower drain outlets thereof comprising a rigid pipe having an inlet at which it is adapted to be temporarily connected with said outlets, and means for producing suction in said pipe, said pipe being of such length that it extends from such an outlet to which it is applied substantially to the side edge of the automobile, and 100 means on said pipe for controlling the production of suction therein by said first-named means. 95

12. Apparatus for evacuating the crank cases of automobiles through lower drain outlets thereof comprising, a conduit comprising a flexible pipe section and a rigid pipe section, the inlet end of said rigid pipe section being adapted for detachable communication with said outlets of crank cases and 105 of such length that it extends from such an outlet to which it is applied, substantially to the side edge of the automobile, means for producing flow of the lubricant from said outlet through said conduit, and means on 110 said rigid pipe section for controlling said first-named means.

13. Apparatus for evacuating the crank cases of automobiles through lower drain outlets thereof comprising, a rigid pipe having an inlet at which it is adapted to be detachably connected with said outlets, means for producing flow of the lubricant through said pipe, said rigid pipe section having a hand grip, and means on said grip for controlling 115 said first-named means, said rigid pipe section being of such length that it extends from such an outlet to which it is applied substantially to the side edge of the automobile. 120

14. An apparatus for evacuating the crank 125

cases of automobiles through a lower drain outlet, comprising a check valve in said outlet, a conduit comprising a flexible pipe section and a rigid pipe section, means on the 5 inlet end of said rigid pipe section for detachably engaging said outlet and opening said check valve, said pipe being of such length that it extends from the outlet to which it is applied substantially to the side edge of 10 the automobile, and means for controlling the flow of oil into said conduit for discharge therethrough.

15. The combination with an oil receptacle, such as the crank-case of an automobile, of a 15 discharge outlet below the normal oil level in the receptacle, a valve for said outlet, a pipe-device fitted to be applied to said outlet, means on said pipe-device for opening said valve, and means for exerting suction in said 20 pipe device.

16. Apparatus for evacuating the crank cases of automobiles through bottom drain outlet thereof comprising a valve for said outlet, a rigid pipe provided at its intake end 25 with means adapted to actuate said valve and seat therein, and means for producing suction in said pipe, said pipe being of such length that it extends from such an outlet when applied thereto substantially to the side 30 of the automobile.

17. Apparatus for evacuating the crank cases of automobiles through the bottom drain outlets thereof comprising a valve for said outlet, a conduit consisting of a flexible pipe 35 section and a rigid pipe section, said rigid section being provided at its intake end with means adapted to seat in and actuate said valve, and means for producing suction in said conduit, the length of the rigid part of 40 said conduit being such that it extends from the outlet to the side of the automobile.

18. The combination with an oil receptacle, such as the crank-case of an automobile, to be evacuated of its oil-content and containing 45 a valve-equipped bottom discharge outlet, of means for evacuating said receptacle comprising a pipe device adapted to be applied to said discharge outlet for flow of oil into said pipe device, means for exerting suction in said pipe device, and means on said pipe device for controlling said second-named means.

HERMAN J. ENGBRECHT.
